(57) **CLAIM**

The ornamental design for a display screen with animated graphic user interface, as shown and described.

DESCRIPTION

The present invention is related to co-pending non-provisional application entitled “App Synchronized with Lighted Physical Design Element on Document Processing Apparatus”, U.S. patent application Ser. No. 16/229,253 filed on Dec. 21, 2018, which has issued as U.S. Pat. No. 10,623,596 on Apr. 14, 2020.

FIG. 1 is a front view of a display screen with animated graphic user interface showing a first image of a first embodiment of the claimed design;

FIG. 2 is a second image thereof;

FIG. 3 is a third image thereof;

FIG. 4 is a fourth image thereof; and,

FIG. 5 is a fifth image thereof.

The broken lines show a display screen with graphic user interface and are included for the purpose of showing portions of the article which form no part of the claim.

The appearance of the display screen sequentially transitions between the images shown in FIGS. 1-5. The subject matter in this patent includes a process or period in which the display screen changes. This process or period forms no part of the claimed design.
